UNITED STATES PATENT OFFICE.

SAMUEL FUCHS, OF COLUMBUS, OHIO.

DESIGN FOR A BUTTON, BADGE, EMBLEM, OR ARTICLE OF A SIMILAR NATURE.

54,076.

Specification for Design.

Patented Nov. 4, 1919.

Application filed May 17, 1919. Serial No. 297,960. Term of patent 3½ years.

To all whom it may concern:

Be it known that I, SAMUEL FUCHS, a citizen of the United States, residing in the city of Columbus, in the county of Franklin and State of Ohio, have invented a new, original, and ornamental Design for Buttons, Badges, Emblems, or Articles of a Similar Nature, of which the following is a specification, reference being had to the accompanying drawing, forming part thereof.

Figure 1 of the drawing shows a front

view of a button, badge, emblem, or article of a similar nature of my new design with the colors used therein, and Fig. 2 shows a side view thereof.

I claim:

The ornamental design for a button, badge, emblem, or article of a similar nature, as shown.

In testimony whereof I affix my signature hereto.

SAMUEL FUCHS.
